US00D813036S

(12) **United States Design Patent** (10) Patent No.: **US D813,036 S**
(45) Date of Patent: **** Mar. 20, 2018**

(54) **TRAY FOR BAGS CONTAINING LIQUID**

(71) Applicant: **Parmalat Canada Inc.**, Etobicoke (CA)

(72) Inventor: **Sidney Scott Prince**, Hamilton (CA)

(73) Assignee: **Parmalat Canada Inc.**, Etobicoke (CA)

(**) Term: **15 Years**

(21) Appl. No.: **29/585,178**

(22) Filed: **Nov. 21, 2016**

Related U.S. Application Data

(62) Division of application No. 29/504,281, filed on Oct. 3, 2014.

(30) **Foreign Application Priority Data**

Oct. 3, 2014 (CA) 155896

CLAIM

The ornamental design for the tray for bags containing liquid, as shown and described.

DESCRIPTION

FIG. 1 is a perspective view of the tray for bags containing liquid showing my new design;

FIG. 2 is a front view thereof;

FIG. 3 is a left view thereof;

FIG. 4 is a right view thereof;

FIG. 5 is a top view thereof;

FIG. 6 is a bottom view thereof; and,

FIG. 7 is a cross-section view thereof taken along line 7-7 of FIG. 1.

1 Claim, 5 Drawing Sheets
